UNITED STATES PATENT OFFICE.

JAMES L. STUART, OF NEW YORK, N. Y.

VESSEL FIRE-EXTINGUISHING APPARATUS.

Specification of Letters Patent No. 32,389, dated May 21, 1861.

To all whom it may concern:

Be it known that I, JAMES L. STUART, of New York, in the county and State of New York, have invented, made, and applied to 5 use a new and Improved Apparatus for the Extinguishment of Fires on Shipboard, which I term the "Hydraulic Safety Machinery;" and I do declare the following to be a full, clear, and correct description 10 thereof, reference being had to the accompanying drawings, and to the letters of reference marked thereon, in which—

Figure 1 is a side view, showing outside of vessel. Fig. 2, a longitudinal vertical section of the same. Fig. 3, a top view of the same, one half, showing portions of the top of the rectangular tube A removed. Fig. 4, a side elevation of the cast iron frame G. Fig. 5, a sectional view of 20 the same. Fig. 6, a top view of the same, showing openings for the slides N N. Fig. 7, a cross section of the same. Fig. 8, a view of one of the valves placed in the side of the tube A forward of the pump H, to 25 be used in case of a leak. Fig. 9, a longitudinal section of the mast pedestal W, showing the valves X and the rod Y. Fig. 10, a top view of part of the steering apparatus, showing the indicator 27, the grooves 28, 30 and the steering wheel 29. Fig. 11 shows the safety apparatus used in connection with the present mode of propelling. Fig. 12, a horizontal section of the same.

In the drawings, like parts of the invention are indicated by the same letters of reference.

The nature of my invention consists in the construction and operation of a new and novel apparatus to be used in connection 40 with the means of propulsion for the extinguishment of fires on shipboard.

To enable those skilled in the arts to make and use my invention I will speak of the construction and operation of the same.

45 In connection with my improved safety apparatus I employ (1) a new and novel means of propulsion; (2) a new and novel means for the discharge of water, in the case of a serious leak; (3) a new and novel mode of steering.

N N show two slides of iron, inclosed in the frame G and working in the same, the frame G being grooved as at O, Fig. 7, for this purpose. These slides N N are grooved 55 at their bottom edge and are provided with rubber-packing to prevent the water from

entering the main pipe A, when the slides N N are depressed or closed. These slides N N pass through the packing boxes l l resting upon the plate of metal K. They are 60 provided at their upper ends with racks, one of which is shown at M Fig. 2, gearing into the pinion O upon the shaft P, said shaft P being operated and operating in turn the slides N N by means of the spoke-wheels 65 Q Q placed on each end of it.

R R' show two tubular masts provided with flanges S S', to secure them to the mast pedestals W W' resting upon the tube A. These pedestals W W' contain each two 70 valves as at X X', opening upward for the admission of water into the tubular masts R R', said valves X X' being closed by depressing the rods Y and Y', while by elevating these rods Y and Y' the valves are 75 opened and the water allowed to enter the tubular masts R R'.

The masts R R' may be provided at the bottom with stop-cocks to allow the water to escape therefrom, into the hold of the vessel, whence it may be pumped out, the rotary pump H being provided with stop-cocks p p for this purpose.

T T' show pipes connected with the tubular masts R, R', and provided with hydrants 85 t, to which may be attached hose, (V) while by means of the stop-cocks u, u', u², u³, water may be shut off from either one side or the other of the vessel. Similar slides to those shown at N N are placed in the bows of the 90 vessel and may be arranged and operated in the same manner or in an equivalent way.

Operation: In case of fire, the hose is attached to any of the hydrants (t) desired. If the ship be propelling bows first, the rod 95 Y is raised the valves as at X open by the pressure of the water below and the water rushes up the tubular mast R, from the fact that the branch tubes B B are smaller "aft" than "forward." In case the quantity of 100 water thus supplied be not sufficient, it may be increased by depressing the slides N N previously described. The water thus forced into the tubular mast R passes through the pipes T T' to the hydrants t, and is thrown 105 upon the fire by means of hose V as previously described. After the fire has been extinguished, the rod Y is depressed, thereby closing the valves as at X, the stop-cock at the bottom of the mast R is opened and 110 the water flows from the mast pedestal W into the hold, whence it is pumped out as

previously stated. In case the vessel be propelling stern first, the rod Y' is raised, slides similar to N N are depressed, thus introducing the water into the tubular mast R' and the operation just described is gone through with.

It will be observed that each of the tubular masts is provided with a throttle valve α^2 , which, in case of fire occurring in the 10 rigging or in the vicinity of the masts, may be opened and allow the water to be forced out of the mast head and when desired the valves α^2 may be opened and the water be elevated to the mast head as a means of testing 15 the strength of the tube A.

In Fig. 11, the apparatus for the extinguishment of fire on shipboard, is shown used in connection with the present mode of propelling, in which case I employ the rectangular tube A, the rotary pump H, the slides N² N³ placed on each side of the pump H, the throttle valves α^4 α^4 opening communication between the tube A and the tubes B³ B³ of the fire department; also the valves 20 10 and 11 placed as shown in Fig. 2. Levers marked 40 are used to operate the throttle valves α^4 α^4 , and 41 shows a wheel on the side wheel or propeller shaft 42 gearing into the shaft L and operating the rotary pump H. 25 30

Operation: In case of a fire and the driving wheel I moving in the direction of the arrow, the slide N³ and the throttle valve α^4

are opened, the latter by means of the lever 40. The water rushes through the tube A as 35 shown by the arrows and up the tube B³, and thence passes through the pipes T T' to the hydrants t, to which is attached hose V and is thrown upon the fire as previously described. If the wheel I be running in the opposite direction, the slide N² and throttle valve α^4 are opened and the water ascends 40 the tube B³ and the operation previously described is repeated. When the fire has been extinguished and the hose v having been removed, air is admitted through the opened 45 hydrants t, the throttle valve α^4 and the slide N³ being opened, the water is discharged by means of the tube A through an aperture in the side or bottom of the vessel. 50

I do not of course desire in the employment of my invention to limit myself to the exact arrangement of parts as shown.

Having thus described my invention what I claim therein as new and desire to secure 55 by Letters Patent is—

The combination of the rotary pump H, slides N N tubular masts R and R', valves X and X' and pipes T and T' provided with hydrants t, when combined and operated as 60 shown and for the purpose set forth.

JAMES L. STUART.

In presence of—

A. SIDNEY DOANE,
C. O. GORDON.
